UNITED STATES PATENT OFFICE

KARL ERNST WENZEL, OF HAMBORN-ON-THE-RHINE, GERMANY, ASSIGNOR, BY MESNE ASSIGNMENTS, TO THE HANNAUER CAR RETARDER COMPANY, OF CHICAGO, ILLINOIS, A CORPORATION OF ILLINOIS

TRACK BRAKE

Application filed October 18, 1926, Serial No. 142,284, and in Germany October 28, 1925.

My invention relates to improvements in track brakes for railways, and more particularly in track brakes comprising a pair of brake shoes located at opposite sides of each rail, one or both shoes being rockingly mounted and one having a flange on which the wheel of the vehicle to be braked rolls, so as to depress the brake shoe to force the same into braking contact with the side face of the wheel, the braking power depending on the pressure of the car wheel on the flange. An object of these improvements is to provide a brake of this type in which the braking action is improved, and with this object in view my invention consists in supporting a rocking member cooperating with the brake shoe so that it is capable of rolling with its end on its support. For the purpose of explaining the invention several examples embodying the same have been shown in the accompanying drawings, in which the same letters of reference have been used in all the views to indicate corresponding parts. In said drawings, Figure 1 is a sectional elevation of one form of track brake embodying the invention, showing the track brake associated with a part of the car wheel; Figures 2, 3 and 4 are similar sectional elevations showing modifications of the brake; Figures 5 and 6 are views corresponding to Figures 3 and 4 of modified forms of the device. Figure 7 is a sectional view taken on the line 7—7 of Figures 3 and 4. In the modification shown in Figure 1 my improved track brake includes supporting means or base *e* disposed transversely of the rail *r* and formed with bearing faces *d* and *d'*, the rail being disposed on any suitable fixed foundation *r'* shown in this and the succeeding modifications as separate structural members supporting a wooden block on which the track rail is mounted. To the face *d'* a brake shoe in the form of a rail *f* is fixed, the head of the said rail being in position for engaging the inner face of the car wheel *g*. The outer face of the car wheel is adapted to be engaged by a brake shoe *a*, which may likewise be in the form of a rail, which rail however is located so that it engages the car wheel with the side of its head, and so that its flange *a'* is in position whereby the car wheel, moving through the track brake, rolls thereon. The rail *a* is carried by a rocking member or lever *b*, the outer end *c* of which is rounded or cam shaped. The inner end of the lever is supported on a spring *s* capable of holding the rail in braking position but yieldable to the pressure imposed by the car wheel on the flange *a'*. The slide or base *e* may be movably supported on a member or support such as shown in Frolich Patent No. 1,635,989, granted July 19, 1927, adapted to be raised by mechanism such as shown in this patent, to move the shoes from inoperative position to an operative position with respect to the rails *r* whereby car wheels operating along the rails *r* may be contacted by said shoes to effect braking action. When a car moves through the track brake *e* when the brake is in operative position, the wheels roll on the flange *a'*. Thereby the rail *a* is forced downwardly, and by reason of the toggle action of the lever *b* the braking pressure of the head *a* on the wheel *g* is increased according to the weight of the car. In applying the brakes, it will be seen that the shoe *a* is pressed toward the left, as viewed in Figure 1, thereby moving or tending to move the slide *e* toward the left to apply braking pressure through the shoe *f* to the wheel *g*. When the slide is in lowered inoperative position, the wheels pass through the brake mechanism clear of the shoes whereby no operation is effected. In Figure 2, I have shown a modification in which the rocking lever *b* is not directly connected to the rail *a*, but in which it is jointed by a bolt *i* to an arm *h* of a member having a part *k* directed downwardly and engaging a pin *n* mounted on the slide or base *e* through a vertically disposed slot *m*. Otherwise the construction is the same as that described with reference to Figure 1, the same letters of reference having been used to indicate corresponding parts. The arm *h*, the arm *k* and the pin and slot connection *n*, *m* provide a parallel guide for

the rail a , the rail normally being resiliently supported by spring s provided on the slide e and engaging bracket z carried by member h . In operation of this modification, it will be assumed that the lifting mechanism for the slide e is similar to that indicated in connection with the modification illustrated in Figure 1; then when the slide has been disposed in a position where the shoes are operative to effect braking operation of the wheel g , the shoe a is engageable by the wheel g . It will be understood that the shoe a in this and the succeeding modifications is maintained in a raised position with respect to the slide e by means such as a spring s disposed between bracket z and slide e as explained above; i. e., in a position where the pin n contacts the lower part of the slot m . Wheel g contacting shoe a tends to move the slide e toward the left, as viewed in Figure 2, through the lever b^2 to thereby set the shoe f . Contact between the lower flange of the shoe a moves said shoe downwardly, rocking movement being effected through the cam c and the surface d , the shoe a moving downwardly substantially parallel to the rail r due to the guide m and the rolling contact between c and d .

The modification shown in Figure 3 is similar to the one shown in Figure 2, with the exception, however, that the lever b^3 is jointed or pivoted to the slide or base e by means of a bolt o , and engages the arm h with a rounded or cam end c' , the said rounded end being an arc of a circle concentric with the bolt o .

As a matter of fact, in lieu of the lever b^3 a roller of substantially the disposition as indicated at p in Figure 5 may be provided to function similarly to the lever b^3 of Figure 3. In the construction as shown in Figure 5 the roller p is pivotally mounted as at o to the support e and contacts the member h which loosely mounts the shoe a for translational movement to the support e . The shoe a is resiliently supported on the support e through the spring assembly s . While the member b^3 in the construction shown in Figure 3 will be kept in working contact with the element h by friction, the position of the member b^3 can be assured by the provision of the resilient support j . The resilient support j may consist essentially of two side members t integrally attached to the support e as at t' , each side member provided with arcuate slots w adapted to receive the bolt v , which extends through the lever b^3 , said bolt limiting the upward movement of the member b^3 .

I have also provided a spring x which will always bring the member b^3 in readiness, as shown in Fig. 7, and is attached to the support e as at w' , which is also applicable to the modification shown in Fig. 4.

In the modification shown in Figure 4, the

lever b^4 is in limited rolling engagement at both ends with the arm h and the face d by means of stops d^2 which are secured to the support e . These stops d^2 preventing the disengagement of the member b^4 from the face d and the arm h , and the said ends are curved along a circle p' . Also, in this case, in lieu of the lever b^4 a roller such as shown at p' in Figure 6 may be used to function in a manner similar to the lever b^4 in Figure 4. As in the case of the lever b^3 both in the construction shown in Figures 4 and 6, the resilient support j may be provided to maintain the lever b^4 and the member p' in operative relation with respect to the support e and the supporting member h . In using the roller construction p' such as shown in Figure 6, the necessity arises that the spring type of support be applied to the axis of the roller. That is, the member v will be on the axis of the member p' by which the upward movement of this axis is limited by the pulling anchor, while the downward movement will be retarded by resting the roller on the bearing or support e . The spring will always bring the roller p' in readiness in the same manner as the spring members of the construction b^4 , as will readily be appreciated.

While in describing the invention reference has been made to particular examples embodying the same, I wish it to be understood that my invention is not limited to the constructions shown in the drawings, and that various changes be made in the general arrangement of the apparatus and the construction of its parts without departing from the invention.

I claim:

1. In track brake mechanism, the combination of a brake shoe associated with a rail, a support for said shoe, a member carrying said shoe and pivotally mounted on said support, and cam means disposed between said shoe and support whereby movement of said shoe imparts movement to said support.

2. In track brake mechanism, the combination of a track rail, brake shoes disposed on both sides of said rail for imparting braking action to wheels operative on said rail, a support for said shoes, means carrying said shoes pivotally mounted on said support, and cam means between one of said shoes and said support whereby movement of said shoe by said wheels moves said support to move said other shoe to braking position.

3. In track brake mechanism, the combination of a track rail, brake shoes disposed on both sides of said rail for imparting braking action to wheels operative on said rail, a support for said shoes, supporting means between said support and one of said shoes, and means including a cam disposed between one of said shoes and said support whereby said shoe is depressed in a direction substantially

parallel to and by a wheel operating along said rail and said other shoe is moved to braking position.

4. In track brake mechanism, the combination of a brake shoe associated with a rail, a support for said shoe, supporting means between said support and shoe, and means including a plurality of cams disposed between said shoe and support whereby movement of said shoe is imparted to said support.

5. In track brake mechanism, the combination of a track rail, brake shoes disposed on both sides of said rail for imparting braking action to wheels operative on said rail, a support for said shoes selectively movable to effective braking position, and cam means between one of said shoes and said support whereby movement of said shoe by said wheels moves said support to move said other shoe to braking position.

6. In track brake mechanism, the combination of a track rail, brake shoes disposed on both sides of said rail for imparting braking action to wheels operative on said rail, a support for said shoes selectively movable to effective braking position, resilient means for maintaining one of said brake shoes in wheel engaging position, and cam means between said shoe and said support whereby movement of said shoe by said wheels moves said support to move said other shoe to braking position.

7. In track brake mechanism, the combination of a brake shoe associated with a rail, a support for said shoe, and means connecting said support and shoe whereby said shoe is depressed in a direction substantially parallel to and by a wheel operating along said rail, said means including a member pivotally mounted with respect to said shoe and cooperating therewith and contacting said support, and a shoe fixed to said support on the opposite side of said rail from said first named shoe and movable into wheel braking position by movement of said first named shoe.

8. In track brake mechanism, the combination of a brake shoe associated with a rail, a support for said shoe, and means connecting said support and shoe whereby said shoe is depressed in a direction substantially parallel to and by a wheel operating along said rail, said means including a member in rolling contact with said support and between said shoe and support.

9. In track brake mechanism, the combination of a brake shoe associated with a rail, a movable support for said shoe, means connecting said support and shoe whereby said shoe is depressed in a direction substantially parallel to and by a wheel operating along said rail, said means including a member secured to said shoe and loosely connected for translational movement to said support, and

a shoe fixed to said support on the opposite side of said rail from said first named shoe and movable into wheel braking position by movement of said first named shoe.

10. In track brake mechanism, the combination of a brake shoe associated with a rail, a support for said shoe, means connecting said support and shoe whereby said shoe is depressed in a direction substantially parallel to and by a wheel operating along said rail, said means including a member secured to said shoe and loosely connected to said support, and a member pivoted to said last named member and contacting said support.

11. In track brake mechanism, the combination of a brake shoe associated with a rail, a support for said shoe, means connecting said support and shoe whereby said shoe is depressed in a direction substantially parallel to and by a wheel operating along said rail, said means including a member secured to said shoe and loosely connected to said support, and a member pivoted to said support and freely contacting said last named member.

12. In track brake mechanism, the combination of a brake shoe associated with a rail, a support for said shoe, means connecting said support and shoe whereby said shoe is depressed in a direction substantially parallel to and by a wheel operating along said rail, said means including a member secured to said shoe and loosely connected to said support, and a member in rolling contact with said last named member and support.

13. In track brake mechanism, the combination of a track rail, brake shoes disposed on both sides of said rail for imparting braking action to wheels operative on said rail, a support for said shoes, supporting means between said support and one of said shoes, and means disposed between one of said shoes and said support and including a member loosely pivoted to said support for sliding movement with respect thereto whereby said shoe is depressed in a direction substantially parallel to and by a wheel operating along said rail and said other shoe is moved to braking position, said other shoe being fixed to said support.

In testimony whereof I hereunto affix my signature.
